(57) **CLAIM**

The ornamental design for an electronic display with a graphical user interface, as shown and described.

DESCRIPTION

FIG. 1 is a front view of an electronic display with a graphical user interface; and,

FIG. 2 is a second embodiment thereof.

The broken lines showing an electronic display with a graphical user interface the illustrate portions of the article, and form no part of the claimed design.

The dashed lines included between the icons that are included within the embodiment of FIG. 2 but disclaimed in FIG. 1 form no part of the claimed design of the first embodiment. The positioning of these lines forms no part of the claimed design of any embodiment.
